APPARATUS FOR PACKETING SMALL QUANTITIES OF GRANULAR OR PULVERULENT MATERIAL

William Sumner and Frank Sumner, Liverpool,
EnglandApplication November 30, 1936, Serial No. 113,388
In Great Britain December 6, 1935

12 Claims. (Cl. 93—3)

This invention relates to apparatus for putting up small quantities of granular or pulverulent material such as medicinal powders or the like into flat paper packets. Such powders are at present packeted in narrow flatly folded paper wrappers, a sheet of paper being formed with a series of parallel folds within which the powder is enclosed, the open ends of the packet being then turned over one upon another, the open ends being left either unconnected or tucked one within the other, the latter operation being done by hand labour.

According to this invention a pad of wrapper sheets is spring-urged against stops, each first or outer sheet in the pad being taken therefrom sequentially by the action of two gripper bars which while spaced apart are pressed into contact with the outer sheet, the bars then closing to nip the sheet and form the first or sheet doubling fold, one part of the doubled sheet being slightly longer than the other to form a lip. The doubled sheet in V-formation and gripped by the bars at the fold is pulled from the pad and held by the grips in a vertical position with its open top above, fingers then engaging the longer lip of the folded sheet to open it ready to receive a measured quantity of powder which is deposited therein. The grips then open permitting the folded sheet containing the powder to fall between a folding plate and two rollers or the like. Subsequently the plate closes the doubled sheet and in so doing presses the lip against the lower edge of a rocking lip-folding bar, which action turns the lip down; at the same time the bar slightly rotates to nip the lip crease. The folding plate then slides down clear of the lip and the folded wrapper, and a horizontal blade advances doubling and forcing the packet between the rollers to impart a second doubling fold. This packet doubling blade pushes the doubled packet beneath an apertured table against which it is left, held by a spring support, on the retreat of the blade. End folders carried on pivotal arms then turn over the outer ends of the packet, one upon another on the table, and when the overlapped ends are to be connected together a punch is caused to descend through the overlapped ends into the aperture in the table, the punch cutting out a tongue from the paper layers in each end, the tongue depending in the aperture. On retreat of the punch, the enclosed packet, with its ends connected by the punched tongue, is ejected from between the spring support and the table by the next entering doubled packet, the completely folded packet falling on to a tipping tray on which it is consolidat-

ed by the compression of a pad. On the release of the compression pad, the tray is tilted and the completed packet containing the powder falls from the machine. Such an apparatus may be combined with a weighing or measuring device for delivering predetermined quantities of powder into the packet at the stage when the V-folded sheet is opened by the fingers. The several operations of wrapper folding, powder delivering, and tongue punching, are all controlled by cam's or the like on one main shaft having an oscillating movement consisting of complete revolutions in opposite directions successively, which movements may be imparted either manually from a handle, or by power, such as a motor, reciprocating a rack engaging a pinion on the main shaft.

Apparatus in accordance with this invention is illustrated in the accompanying drawings in which:—

Fig. 1 is a front elevation showing the cam gear for operating the wrapper grip arms and fingers, and in section the powder supply hopper and powder measuring and delivering device. 20

Figs. 2 and 3 show successive closing operations of the wrapper grip arms. 25

Fig. 4 is a rear elevation showing the mechanism for operating the powder delivery and hopper agitator. 30

Fig. 5 is an end view looking from the left-hand or hopper side of Fig. 1. 35

Fig. 6 is a fragmentary sectional front elevation on the line 6—6 of Fig. 5 showing mechanism for operating the lip folder, packet doubling blade, tongue punch and packet consolidating mechanism. 40

Fig. 7 is a fragmentary sectional front elevation on the line 7—7 of Fig. 5 showing cam mechanism controlling the movements of the folder plate and doubling blade. 45

Fig. 8 is a view of part of Fig. 7 showing in chain dotted lines the lip bar and folder plate closed and in dotted lines the latter being lowered. 50

Figs. 9 to 12 inclusive are diagrammatic sections showing in order of occurrence the first four folding operations on the wrapper. 55

Fig. 13 is an end view looking from the right-hand side of Fig. 1 showing the end folders, punch and packet consolidating mechanisms, the hopper at the rear being omitted. 60

Fig. 14 is a diagrammatic view of the fifth folding operation showing the packet ends being turned over by the folders. 65

Fig. 15 is a perspective view of the packet corresponding to this fifth operation. 70

Fig. 16 is a detail view partly in section show- 75

ing the end folders in their final position closing the packet, the punch being about to descend.

Fig. 17 is a perspective view of a completed packet.

5 Fig. 18 is a sectional plan of the hopper on the line 18—18 of Fig. 1 showing the agitator and powder consolidating plate, and

Fig. 19 is a plan view of the powder measuring and delivering device.

10 The apparatus comprises spaced side plates 1, 2 in which is journaled the main shaft 3 carrying cams and like rotary elements by which the mechanisms effecting the various operations of folding the wrapper, delivering powder therein, 15 punching and consolidating the packet, are controlled, a complete sequence of operations being performed during a double revolution of the shaft 3 in opposite directions. A pad consisting of a number of vertically disposed wrapper sheets 20 4, Figs. 1 and 5, is supported on horizontal guides 5 and pressed against upper and lower bar stops 6 by a back plate 7 engaged by a lever 8 pivoted at 9 and urged by springs 10 to feed the wrappers towards stops 6.

25 *Wrapper selection and first wrapper folding mechanism*

A pair of rubber faced grip bars 11 extending horizontally are carried on gripper levers 12 on 30 each side of the machine pivotally mounted at 13 on arms 14 which are in turn pivoted at 15 to rocker arms 16 secured on a spindle 17 journaled in the side plates of the machine. Arms 14 and 16 may be otherwise associated for relative movement. The gripper levers 12 are controlled by springs 18 so that they tend normally to open and they have curved recesses or bays in their outer edges with which pins 19 on the 35 rocker arms 16 cooperate in such manner that when arms 14 and 16 are together, the pins are opposite the bays and the levers 12 may open as in Fig. 1 but when arms 14 and 16 are apart as in Fig. 3 the pins 19 move out of the bays along the levers 12 and the latter close. The grip levers 12 are rotated from their lower position 40 shown in dotted lines, Fig. 1, to a position, shown in full lines, against the pad of wrappers 4, by rotation of the spindle 17 carrying the rocker arms 16 and arms 14 closed and the grips open. This movement is effected by a pin 20 on a cam 45 21 on the main shaft 3 entering, as the cam has rotated in the direction of the arrow, jaws 22 on a link 23 pivoted to a crank 24 on the spindle 17, the downward movement of pin 20 raising the grips to the position shown in full lines, Fig. 1, with the bars 11 pressing against the first wrapper of the pad. At this position, the tips of the arms 14 meet and are arrested by stops 50 25 on the side plates, the continuing movement of the pin 20 turning the rocking arms 16 further forward towards the pad Fig. 2, so that the pins 19 ride out of the bays in the grip levers 12 closing the latter against the action of the spring 18, and ultimately tightly nipping the front 55 wrapping sheet of the pad and imparting to it the first half fold, Figs. 3 and 9. The levers 12 in this closed position are tightly wedged between the pins 19. The engaging position of the grips relatively to the height of the wrappers 60 in the pad is such that this first fold is formed non-centrally not quite half way up the sheet, so that one of the doubled parts of the wrapper is longer than the other, Fig. 9, forming an extension or lip 26. When, on the reverse rotation 65 of the shaft 3, the open arms 16 and 14 return

with levers 12 held closed by the frictional grip of the pins 19, as in Fig. 3, drawing the nipped wrapper from the pad past the stops 6, the arms 14 meet other stops 38 on the side plates, the V-folded wrapper being in a vertical position, and while it is still nipped, fingers 27 carried from a spring controlled spindle 28 are released to press the projecting lip 26 of the larger side against a curved plate 29 and partly open the V-fold. The cam pin 20 then passes 10 out of the jaws 22 leaving levers 12 closed and still holding the wrapper. At the beginning of the next reversal of shaft 3 another pin 20a on the cam engages under the prong 20b lifting the link 23 slightly, which causes the rocker arms 15 16 to continue their downward movement and close against the arms 14 still arrested by stops 38, the pins 19 moving opposite the bays in the grip levers 12, permitting them to open and release the wrapper 4 which remains suspended 20 as shown in dotted lines Fig. 1 by its lip 26 held by the fingers 27. At this stage a measured quantity of powder is delivered into the valley of the folded wrapper as explained later and the fingers 27 are immediately released, the wrapper weighted with its powder content falling on to a stop 34, Fig. 7. The spindle 28 carrying the fingers 27 is controlled by a spring 28a tending to engage the finger grip and angular movement of the spindle to release the grip or permit it 30 to close is controlled by the contour of the cam 21 the edge of which engages pin 31 on lever 32 pivotally connected by link 33 to a short crank on the spindle 28.

35 *Lip-folding mechanism*

When the filled wrapper 4 is released by the fingers 27 and falls on the stop 34, the sides of the wrapper lie in open V-formation as shown in Fig. 7 between a folder plate 36 and two horizontal rollers 37 journaled in the side plates, the upper roller being mounted in slots 37b and spring controlled at 37a. The lip 26 of the wrapper in this position projects above the lower edge of a lip-folding bar 38 pivoted at 39. The folding plate 36 is pivotally mounted at 40 in a carrier 41 pivoted at 42, a spring 43 tending to maintain the carrier in its raised position shown in Fig. 7, and the carrier remains in such position while the rollered end 46 of an arm 47 on the carrier rides against the inner convex edge of a cam 44 on the shaft 3, as is occurring in Fig. 7. Pivotal movement of the folder plate 36 while the carrier is in this position is effected by another cam 48 on the shaft 3 engaging pin 49 45 on lever 49a pivoted at 50 and controlled by spring 51, a roller 52 on the lever engaging a resilient blade 53 on the weighted bell crank arm of the folder plate 36. As cam 48 rotates in the direction of the arrow, Fig. 7, the cam 50 hump engages pin 49 rocking the lever 49a, and plate 36 closes the V-fold of the packet sweeping the lip 26 under the lip folder 38, and turning it down as shown in Fig. 6. Simultaneously the lip folder 38 pivots to compress the folded lip 55 being pulled by a rod 54, Fig. 6, connected to a two armed lever 55, the rollered end of one arm being engaged by a cam 56 on the shaft 3. This primary closing of the lip folder is effected by the lower part of the hump 57 on the cam, the 60 plate 36 still remaining beneath the lip. At this point, the flat face 45 on cam 44, Fig. 7, begins to bear against roller 46 on arm 47 depressing the carrier 41 and drawing down the carrier and folder plate 36 from beneath lip folder 38, as 65 70 75 75

indicated in dotted lines, Fig. 8, and immediately the higher part of hump 57 on cam 56, Fig. 6, further rotates lip folder 38 to impart a final crease to the lip. The folder plate 36 is then drawn completely down and held there by the outer convex edge of cam 44, clear of the rollers 37. The wrapper is now folded as shown in Fig. 10.

Packet doubling fold mechanism

As the folded packet with closed lip 26 lies vertically behind the rollers 37, a blade 58, Figs. 6, 7 and 8, slidable horizontally on guides 59, advances to double and push the packet through the rollers, the upper roller opening resiliently, to a position beneath a table 60, Figs. 6 and 14, where it is held by a spring support 61 on the retreat of the blade. The blade 58 is advanced and retracted by the opposite rotations of a crank 62 on shaft 3, the crank pin 63 engaging the slot 64 of a bracket carrying the blade.

End folding mechanism

As indicated in Fig. 14, the ends 4a of the doubled packet project at each side of table 60. On the retreat of the blade 58 these ends are bent up round the table and overlapped by folders 65, Figs. 13, 14 and 16, consisting of flexible plates 65, notched at 68, Fig. 16, to permit passage of a punch 69 and carried on arms 66 pivoted at 67 on the frame. The movements of arms 66 are effected by the oscillation of crank 62, pin 63 on which engages the slotted arm of a lever 70, Fig. 6, on a shaft 71, the other arm of the lever carrying projections 72, set one in advance of the other, engaging heel plates 73 on folder arms 66. As the lever 70 is rocked up from the dotted position to that shown in full lines, Fig. 6, the right projection 72, Fig. 13, first engages its heel plate 73 and raises the right folder 65, the left projection 72 then raising the other folder 65, so that the ends of the packet are overlapped when the folders are finally closed, Fig. 16. The end folders again open to the position shown in Fig. 13, on reversal of crank 62, by projections 72 rising and engaging brackets 74 on the arms 66. The lever 70 which thus operates the end folders 65 also actuates a tonguee punch 69, and packet consolidating mechanism.

Punch mechanism

Mounted above the table 60, as best seen in Figs. 1 and 6, is a punch 69 slidable vertically in guides 75 and so spring controlled at 76 that the punch tends to rise to the position shown in Fig. 1. The punch has a bevelled foot 77 and as it descends passes through notches 68 in the overlapped folders 65 into an aperture in the table 60. When the ends of the packet are folded one upon another and while still held by folders 65, closed as in Fig. 16, the punch 69 descends through notches 68 and punches out from the paper layers of the superposed ends, a tongue 78, Fig. 17, leaving an integral hinge connection, because of the bevelling of the punch foot 77, which is at the rear of the tongue when the packet is being pushed from the table by the next succeeding packet, the tongue being wiped back about its hinge to lie underneath the ends 4a, so that when the packet is subsequently consolidated the tongue interlocks the ends. After the tongue has been formed the punch rises and the end folders 65 open out. The movement of the punch is effected by the rocking of lever 70, to the outer end of which is pivoted at 79 a bowed link 80 connected to an arm 81 pivoted on the frame

and engaging upper and lower pins 82 on the punch bar. A lost motion connection of the link 80 to the arm 81 is provided by a slot 83 in the link engaging a pin 84 on the arm. As crank 62 rocks lever 70 to the position shown in full lines, Fig. 6, the punch is drawn down and rises again when lever 70 is rearwardly rocked, the crank pin 63 not leaving the slotted arm during these movements. When however the pin 83 leaves the slotted arm to engage the slotted bracket 64 of the doubling blade, the spring 76 keeps the slotted arm in the dotted position, Fig. 6, for re-engagement by the crank pin. The packet with its ends folded and connected together by the tongue lock is pushed from the table 60 by the next entering packet.

Packet consolidating and delivery mechanism

The packet falls on a tipping tray 85, Figs. 1, 4, 6 and 13, pivoted at 86, on which it is consolidated by the action of a centrally recessed rubber pad 89 on a flexible arm 90 pivoted at 91 at the side of the machine, the arm being spring controlled and tending to rise to the position shown in Fig. 13. When the bowed link 80 descends to operate the punch an angled shoulder on the link engages the back of arm 90 forcing the pad 89 against the packet and consolidating it on the tray. The packet creases or folds are thus finally "set", and its powder content flattened. When the link 80 again rises allowing the pad 89 to rise under its spring control, a pawl 88 on the link 80 engages an angled arm 87 on the pivot of the tray, tilting the latter to the position shown in chain dotted lines Fig. 13, the packet sliding off the tray, which falls back to the horizontal, being non-centrally pivoted. On the subsequent downward movement of the link 80 the pawl 88 trails idly past the arm 87.

Powder measuring and delivering mechanism

In connection with such a machine any suitable type of measuring or weighing apparatus may be combined or provided to deliver a predetermined quantity of powder into the packet. In so delivering the powder any diffusion into the atmosphere should be avoided as besides the loss of material it would be very deleterious to the workers, particularly in the case of medicinal powders, and further, if the powder be delivered in loose form into a partly folded wrapper it spreads laterally therein beyond the points where the ends are later folded, such folding then resulting in a further loss and diffusion of powder through the open ends. This is prevented by delivering the powder into the folded wrapper as a consolidated lump, thus keeping all the powder in the centre of the packet which may be then folded without diffusion, the powder lump being however not so tightly consolidated but that it may subsequently be spread evenly in the closed packet by compressing the latter. With this object, in the base of the powder supply hopper 92, is journalled a spindle 93 which carries an agitator such as a wire ring 94 and a presser blade 95, Figs. 1 and 18. A gear wheel 104, Fig. 4, is oscillated by a pinion 105 on the main shaft 3, Fig. 4, and gear 104 reciprocates a rod 103, a long pin 114 on which controlled by a spring 112 engages a notch 113 in a peripherally grooved disc 102 on the spindle of which is an arm 100, another rod 116 engaging and rocking a forked lever 117 on the spindle 93, a certain amount of lost motion being provided for. The arm 100 is pivotally connected at 101 to a channel section powder carrier 97, the angular sweep of the arm 75

causing the carrier intermittently to enter the hopper, withdraw a measured quantity of powder and deliver it into a wrapper. A roller 106 on one end of the pivoted carrier is constrained by the pull of a spring 115 to ride against a track bar 99 of such contour that the carrier enters an aperture 96 in the hopper horizontally, Fig. 1, but at its terminal return movement tilts vertically, Fig. 4. A measuring spoon 98 is so pivoted in the carrier at 109 that it lies therein as the carrier enters the hopper, the presser 95 being then raised, shown in dotted lines, and the agitator 94 moved, loosening the powder which falls into the uncovered recess of the spoon 98. The rod 116 then turns down the presser blade 95 consolidating the powder in the semi-circular recess of the spoon. The carrier, during filling is stationary in the hopper, the pin 114 having passed up out of notch 113, spring 112 extending, as shown in dotted lines, Fig. 4, the rod 103 riding in the disc groove and re-engaging the notch on descent. On withdrawal of the carrier excess powder is wiped off by the top edge of aperture 96. As the carrier reaches the end of its delivery movement, it tilts to a vertical position, Fig. 4, due to the sharp curve of the track bar 99, and its two deep rear wings 107 engage within a fixed channelled member 108 to form an enclosed shute. Simultaneously an arm 110, Fig. 1, on the spoon pivot meets a curved abutment 111, tilting the spoon forward from the now vertical carrier, Fig. 6, the spoon tip striking the back of the shute 108 and knocking out the powder lump which falls into the V-folded wrapper 4, the consolidation preventing lateral spread of the powder on impact.

To ensure that all the powder is delivered, the tilted spoon is given a final shake. After the carrier has been stopped at its delivery position, Fig. 4, and the spoon has tilted, the pin 114 passes on, leaving notch 113 and riding down the disc edge. On the return movement the slipping grip of the pin riding on the disc is just able to slightly lift the arm 100, but directly the pin reaches the notch and is snapped sharply therein by spring 112, this action jerks the arm down again, shaking the inverted spoon just before the carrier begins its movement to the hopper, the spoon falling back into the carrier as the latter assumes a horizontal position.

All the operations described are performed during, and are effected by, one oscillation of the shaft comprising two successive complete revolutions of the main shaft 3 in opposite directions. A clockwise revolution, as viewed in Fig. 1, raises the open grips to the wrappers, closes the grips, raises the punch and consolidating pad and opens end folders, enters carrier in hopper, closes the V-folded wrapper and creases the lip, depresses the folder, releases the lip fingers and advances the doubling blade. An anti-clockwise revolution, withdraws the doubled wrapper from the pad, permits fingers to engage lip of wrapper, retracts doubling blade, opens grips, withdraws and tilts carrier, releases lip fingers, closes end folders, punches and consolidates the packet.

We claim:—

1. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a carrier for delivering material into the valley of the doubled sheet,

rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft. 5

2. Apparatus for packeting material in flatly folded wrappers, comprising, guides for supporting a pad of wrapper sheets, stops for the pad, a spring for urging the pad against the stops, relatively movable grip levers for engaging the pad, relatively movable rocker arms for swinging the grips while open against the pad and closing them to nip, double and withdraw a single sheet to a vertical position, cam controlled toggle links for swinging the rocker arms and effecting their relative movement, a carrier for delivering material into the valley of the doubled sheet, rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft. 10 15 20 25 30

3. Apparatus for packeting material in flatly folded wrappers, comprising, guides for supporting a pad of wrapper sheets, relatively movable grip levers for engaging the pad, relatively movable rocker arms for swinging the grips while open against the pad and closing them to nip, double and withdraw a single sheet to a vertical position, said grip levers being carried on and movably associated with the rockers, relative movement of the rockers opening and closing the 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

4. Apparatus for packeting material in flatly folded wrappers, comprising, guides for supporting a pad of wrapper sheets, relatively movable grip levers for engaging the pad, relatively movable rocker arms for swinging the grips while open against the pad and closing them to nip, double and withdraw a single sheet to a vertical position, said grip levers being pivoted on one rocker, stops for that rocker, bays in the levers, pins on the other rocker co-operating with the bays, relative movement of the rockers opening and closing the grips, cam controlled toggle links for swinging the rocker arms and effecting their relative movement, a carrier for delivering material into the valley of the doubled sheet, rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam mem- 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

bers for actuating the movable parts of the apparatus mounted on a single oscillating shaft.

5. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, fingers for engaging the doubled sheet by its longer side and suspending it when released by the grips, a carrier for delivering material into the valley of the doubled sheet when so suspended, means for releasing the fingers, rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft.

6. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a lip formed by the longer side of the doubled sheet, fingers for engaging the doubled sheet by its lip and suspending it when released by the grips, a carrier for delivering material into the valley of the doubled sheet, rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft.

7. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a carrier for delivering material into the valley of the doubled sheet, rollers between which the doubled sheet is pushed, a blade co-operating with said rollers to redouble the filled doubled sheet in parallel folds by pushing it through the rollers, an apertured table for receiving the folded sheet from the rollers, pivotal folders for overlapping the ends of the redoubled sheet about the table to form a packet, a punch for pressing out a tongue from the overlapped ends into the table aperture, means for pushing the packet off the table to bend the tongue back and lock the ends, and cam members for actuating the movable parts of the apparatus mounted on a single oscillating shaft.

8. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a carrier for delivering material into the valley of the doubled sheet, rollers between which the doubled

sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, a tilting tray on to which the packet is pushed from the table by the following packet, a compression pad for consolidating the packet on the tray, a reciprocating link which compresses the pad and tilts the tray, and cam members for actuating the movable parts of the apparatus mounted on a single oscillating shaft.

9. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a hopper, a carrier for delivering material into the valley of the doubled sheet, a track for guiding the carrier to and from the hopper and tilting it at the delivery position, rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft.

10. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a hopper, a channelled carrier for delivering material into the valley of the doubled sheet, a track for guiding the carrier to and from the hopper and tilting it at the delivery position, rollers between which the doubled sheet is pushed, a fixed channelled member with which the channelled carrier co-operates when tilted to form a closed chute, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft.

11. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a hopper, a carrier for delivering material into the valley of the doubled sheet, a measuring spoon pivoted in the carrier, a presser in the hopper for consolidating material in the spoon, means for tilting the spoon to tip its contents, rollers between which the doubled sheet is pushed, a blade co-operating with said rollers to redouble the filled doubled sheet in parallel folds by pushing it through the rollers, a table for receiving the folded sheet from the rollers, pivotal folders for overlapping the ends of the redoubled sheet about the table to form a packet, and cam members for actuating

the movable parts of the apparatus mounted on a single oscillating shaft.

12. Apparatus for packeting material in flatly folded wrappers, comprising, guides for supporting a pad of wrapper sheets, relatively movable grip levers for engaging the pad, means for pressing the grips while open against the pad and closing them to nip, double and withdraw a single sheet to a vertical position, a hopper, a carrier 10 for delivering material into the valley of the doubled sheet, a track for guiding the carrier to and from the hopper and tilting it at the delivery position, a notched disc, a spring controlled rod engaging and oscillating the disc, an arm for 15 traversing the carrier moved by the disc, said

rod disengaging the notch after the carrier tilts and snapping into re-engagement to jerk the carrier before returning to the hopper, rollers between which the doubled sheet is pushed, a blade co-operating with said rollers to redouble 5 the filled doubled sheet in parallel folds by pushing it through the rollers, a table for receiving the folded sheet from the rollers, pivotal folders for overlapping the ends of the redoubled sheet about the table to form a packet, and cam members for actuating the movable parts of the apparatus mounted on a single oscillating shaft.
